BAG FOR GARBAGE AND THE LIKE

Joseph M. Shapiro, Richfield, Conn.

Application February 24, 1944, Serial No. 523,739

4 Claims. (Cl. 229—55)

This invention relates to bags for holding garbage or the like and has for its object to provide an inexpensive receptacle of neat and pleasing appearance to contain garbage or refuse without emitting unpleasant odors.

In closely populated places such as apartment houses, it has often been customary to dispose of garbage by putting it into metal garbage pails which are customarily left outside apartment entrances in the corridor of the building for collection. Such a practice not only creates an unsightly appearance by reason of the numbers of disposal pails in the corridors, but is also unsanitary as the garbage pails are difficult to maintain in a clean sanitary condition after recurrent use. Furthermore, they usually emit unpleasant odors due to their uncleanliness and because it is seldom possible to seal the covers tightly. The same general problem is encountered in private homes where garbage is burned on the premises or collected by a municipality. In some buildings, it is attempted to avoid the necessity for undesirable garbage pails by providing an incinerator in the basement of the building with chutes leading down to the incinerator from the upper floors. This method requires some form of chute at each floor into which garbage may be dumped. Although this method does away with the necessity for placing garbage pails in the corridors, it is neither sanitary nor free from odors, as garbage is inevitably spilled on the walls of the chute.

In accordance with the present invention, the foregoing disadvantages are obviated by the use of a garbage bag which can be filled with the garbage and then sealed and disposed of in its entirety, after which a new bag may be used. Attempts have heretofore been made to use bags for garbage disposal but they have usually suffered the disadvantage of not closing or sealing properly so that they were untidy and gave off odors. In accordance with my invention, I provided a simple construction at the top of the bag for closing it and preventing the escape of odors, even though the bag may be opened several times during its use for the addition of more garbage or refuse.

A feature of the invention is the use of inner and outer walls for the bag with provision for separating them at the top to permit the introduction of a cover flap into the space between the walls to maintain the bag in a tightly closed position.

An object of the invention is to provide an improved sanitary bag for garbage, refuse and the like.

Another object of the invention is to simplify the handling and disposal of garbage.

Another object of the invention is to provide an inexpensive bag which may be readily closed to minimize the escape of odors.

Another object of the invention is to provide an improved bag which may be readily opened and closed during use and which may be permanently closed when filled.

10 Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein

Fig. 1 is an enlarged perspective view of a bag in accordance with my invention;

Fig. 2 is a perspective view of the bag shown in Fig. 1, the front wall being shown partially broken away;

Fig. 3 is a cross-sectional view taken at line 3—3 of Fig. 2;

Fig. 4 shows the top portion of the bag of Fig. 2 with the cover flap in its closed position;

Fig. 5 is a cross-sectional view taken at line 5—5 of Fig. 4;

Fig. 6 shows the arrangement of Fig. 4 with the sealing tab in its sealed position;

Fig. 7 is a cross-sectional view taken at line 7—7 of Fig. 6; and

Fig. 8 shows a modification of the construction shown in Figs. 1 to 7.

The body of the bag shown in Figs. 1 to 7 is composed of an outer wall 1 and an inner wall 2 which may be of paper or the like; and in the preferred embodiment, the inner and outer walls are made to adhere to each other so as to form a double wall. In its unused condition, the bag

45 is preferably flattened out as shown in Figs. 2 and 3 so as to form a back or posterior wall 3 and a front or anterior wall 4. The top of the back wall protrudes above the top of the front wall so as to provide a closing flap 5. Near the bottom

50 of the bag, the wall is provided with a double fold at 6 and 7 so as to provide maximum capacity when garbage or refuse is introduced. If desired, the body may be formed of more than one section, the sections being glued or joined together as at 55 8 in a well known manner.

The two sheets 1 and 2 forming the wall are made non-adherent to each other at the top of the front wall 4 as illustrated at location 9 in Fig. 3 so that at this position the two walls 1 and 2 may be separated to permit the insertion of the cover flap 5, when folded over, between these two walls 1 and 2, as illustrated in Figs. 4 and 5. There is preferably provided an adhesive seal 10 which may be glued near the top of the rear wall 3 so that after the flap 5 is finally closed as shown in Fig. 4, the seal may be folded over from the back to the front wall and sealed as shown in Figs. 6 and 7.

For the purpose of wet-proofing the bag the inner sheet 2 forming its wall will usually be of a wet-proof material, for example, a reasonably heavy oiled or waxed paper, while the outer sheet 1 need not be moisture-proof, but should be of a durable tough quality.

Modifications from the arrangements shown in Figs. 1 to 7 are permissible. For example, it may be desired to make the separable sheets at the top of the front wall in a section separate from the rest of the body. This construction is shown in Fig. 8, wherein the main portion of the front wall 4 below the top of the bag is made as shown in Fig. 3, with the two sheets 1 and 2 adhering together, while the upper portion of the bag is a separate section 11 forming a band around the top of the bag. At the back wall, the two sheets of the section 11 are made to adhere to each other, whereas at the front wall, the sheets 1 and 2 are not adhered to each other and there is accordingly provided the desired separation forming the space 9 between them for allowing the closure flap 5 to be inserted.

For the purpose of enabling bags to be easily hung on a suitable nail or hook for convenient access, where temporary closing is not required, there may be provided a hole 12 through the cover flap. The hole may extend through the sealing tab or may be made use of by bending the sealing tabs 10 out of the way.

It will be recognized that in accordance with this invention, there is provided a simple inexpensive bag of durable construction which can be used as often as desired until filled and which can easily be kept closed until its final disposition. After a meal, for example, a new bag may be put into use and the garbage or refuse put into it. This will distend the bottom of the bag and partially fill it after which the cover flap 5 may be folded down and inserted between the inner and outer sheets of the front wall as shown in Figs. 4 and 5. Then, after a subsequent meal, more garbage may be put into the bag following which the flap is again folded down into its closed

position. This may be repeated any number of times until the bag is nearly filled, after which, upon final closure of flap 5, the seal 10 is applied as shown in Figs. 6 and 7. The bag is then ready to be put out for collection and a new bag may be put into use. This avoids the necessity for continuous use and cleaning of unsightly garbage pails and avoids their attendant odors. In addition, the handling of the garbage by attendants and collectors is simplified and less odious because the receptacles are clean and sanitary, and the garbage is closed from view. The garbage trucks will be kept sanitary and substantially free from odors.

As various changes may be made in the form, construction and arrangement of the parts herein without departing from the spirit and scope of the invention, and without sacrificing any of its advantages, it is to be understood that all matter herein is to be interpreted as illustrative and not in a limiting sense.

Having thus described my invention, I claim:

1. A double walled garbage bag having an inner wall of moisture-proof material and an outer paper wall enclosing said inner wall, said bag having a flap on one side at its open end, said walls being separable on the opposite side at said open end to permit insertion of said flap therebetween and being bonded together at the other portions.

2. In an open mouthed bag, a double front wall open at the top, a flap extension of the back wall including a perforation and long enough to be bent over and inserted between the faces of the double wall to close the bag, and a strap adhering behind the flap and perforated to register with the flap and adapted to be sealed down over the flap to hold the bag closed.

3. A double walled garbage bag having an inner wall of moisture-proof material and an outer paper wall enclosing said inner wall, said bag having a flap on one side at its open end with a perforation in said flap, said walls being separable on the opposite side at said open end to permit insertion of said flap therebetween and being bonded together at the other portions.

4. A double walled garbage bag having an inner wall of moisture-proof material and an outer paper wall enclosing said inner wall, said bag having a flap on one side at its open end, a strap adhered to the back of the flap and adapted to be sealed down over the flap to hold the bag closed, said walls being separable on the opposite side at said open end to permit insertion of said flap therebetween and being bonded together at the other portions.

JOSEPH M. SHAPIRO.
